STACK SWITCH

Burton E. Shaw, Bristol, Ind., assignor to Penn Electric Switch Co., Goshen, Ind., a corporation of Iowa

Application November 15, 1939, Serial No. 304,558

8 Claims. (Cl. 200—138)

My present invention relates to a stack switch having a novel snap switch unit and temperature responsive mechanism for actuating the same.

One object of the invention is to provide an improvement in stack switch operation over the types of actuating devices now in general use for operating the switch unit of the stack switch from a coiled bi-metal element or other temperature responsive device.

10 Another object is to provide operating mechanism for the switch unit of the stack switch which minimizes the possibility of jarring the stack switch contacts after they have been moved to either closed or opened position and the temperature continues to change.

In this connection it is well known in the art that a desirable characteristic of a stack switch is that the switch will be moved from one position to the other substantially immediately upon a 20 change of temperature in either direction as distinguished from most thermostats which close or open at a predetermined temperature.

Much difficulty has been experienced in providing an efficient slip connection between the temperature responsive element and the switch unit to permit continued movement of the temperature responsive element after the switch has been opened or closed without further affecting the position of the switch until such time as the temperature reverses.

Friction connections have been used but the degree of friction is uncontrollable.

Another method has been used in which a disc with a notched periphery has a leaf spring engaging the notches. This has the disadvantage of considerable movement of the leaf spring as the notched disc continues to rotate after the switch has been opened or closed.

To overcome the difficulties experienced with friction and notched disc connections, I provide a modification of the notched disc connection in which the disc instead of having notches in the periphery has them in one face thereof, a novel actuator for the switch being rotatable relative to the disc and including a leaf spring member provided with ball seats in which balls are seated and pressed thereby into engagement with the notches in the face of the disc.

40 The foregoing, other and further objects of the invention will be apparent to those skilled in the art to which this invention appertains, by reference to the following description, accompanying drawing and appended claims. One embodiment 45

ing drawing wherein the views thereof may be described as follows:

Figure 1 is a front elevation of a stack switch embodying my invention, the cover for the casing thereof being removed.

5 Figure 2 is an enlarged sectional view on the line 2—2 of Figure 1 showing the stack switch in open position.

Figure 3 is a similar view of a portion of Figure 2 showing the stack switch in closed position.

10 Figure 4 is a perspective view of the snap switch unit and its actuator which particularly form the parts of the present invention; and

Figure 5 is a sectional view on the line 5—5 of Figure 2.

15 In the accompanying drawing I have used the reference character C to indicate generally a casing of a stack switch. Within the casing C a panel 10 is provided below which a transformer 12 is supported for supplying current to the various circuits passing through the stack switch. The transformer 12 and several other parts (such as relay contacts 13 and 14 and a safety switch 15) form no part of my present invention.

20 On the panel 10 I mount a snap switch unit 25 S. The snap switch unit S, as shown in Figure 3, comprises a rectangular frame 16 having an open center and between the ends of the frame a buckled leaf spring 17.

25 The leaf spring 17 may be curved in either direction, as shown in Figures 2 and 3. When the curvature is downwardly with relation to the panel 10, contacts 18 and 19 of the stack switch are open, as in Figure 2. When the curvature is reversed they are closed, as shown in Figure 3.

30 The contact 18 is carried by the leaf spring 17, while the contact 19 is a stationary contact carried by a bracket 20. The bracket 20 is secured to the panel 10 by a rivet 21. As shown in Figure 2, the spring 17 has an extension 22 with which a circuit wire 23 may be connected. The wire 23 is one terminal of the switch while the bracket 20 or the rivet 21 is the other terminal thereof. The snap switch unit S may be connected in any suitable stack switch circuit such as one of the kind shown in my Patent No. 2,080,580, of May 18, 1937, and forms no part of the present invention.

35 For actuating the snap switch unit S by reversing its curvature I provide a projection 24 thereon. An actuator A coacts therewith. The actuator A is rotatable on a sleeve 25 which in turn is secured to a shaft 26 by a set screw 27 (see Figure 5). A disc 28 is rigidly secured to the sleeve 25 for rotation therewith by assembling it against a

55

shoulder 29 thereof and spinning or riveting over an end portion 30 of the sleeve. A second shoulder 31 is provided between which and the disc 28 the actuator A is mounted for relatively free rotation.

The shaft 26 is rotatably mounted in a bracket 32 and at its outer end is connected at 33 with a coiled bi-metal element 34. One end of the coil is thus connected at 33 while the other end is connected at 35 to a stationary point such as the bracket 32.

The actuator A is made of leaf spring material having a pair of arms 36. Each arm is provided with a ball seat 37 in which a ball element such as a ball bearing 38 is seated. Each arm 36 then curves around the periphery of the disc 28 as at 39 and has a terminal end 40 serving as a stop means to prevent excessive springing of the arm 36.

20 The disc 28 on one face thereof is provided with an annular ring of relatively closely spaced notches 41. The balls 38 coast therewith under tension of the leaf spring arms 36. Preferably the two balls 38 successively or alternately engage the notches 41 as shown by comparison in Figure 2.

The actuator A further includes a pair of arms 42 terminating in flanges 43. The flanges 43 straddle the projection 24.

30 Practical operation

In the operation of my stack switch when the bimetal element 34 responds to a change in temperature in one direction, the disc 28 will rotate counterclockwise to cause the right hand flange 43 in Figure 2 to engage the projection 24 and bow the leaf spring 17 downwardly. This separates the contact 18 from the contact 19. Upon further change of the temperature in the same direction 40 the notches 41 of the disc 28 will ratchet past the balls 38 with first one ball dropping in a notch and then the other one.

The alternate dropping of the balls in the notches produces in effect an action equivalent to 45 one ball with notches half as closely spaced as illustrated. Since it is impractical to make the notches closer together than illustrated as they could not then have enough depth especially when the disc is formed as a stamping. It is obvious 50 that the alternate engagement of the balls makes it possible to secure a finer division between coaction of the balls with the notches and thereby a smoother action during the further rotation of the disc after the switch has been opened.

55 Upon a reversal of the temperature the disc 28 will rotate clockwise as in Figure 3, first moving the left hand flange 43 to engage the projection 24 and this flange finally urging the projection to reverse the curvature of the spring 17 and thereby 60 close the contact 18 against the contact 19.

Here again after the contact has been closed, the disc 28 may rotate further in the same direction without affecting the contacts as the notches of the disc will merely slip past the balls. Since 65 the springing of the balls and the spring arms 36 is in a direction axially of the disc the slight jar-ring caused thereby will not be transmitted in the plane of the disc to affect the closed condition of the contacts.

70 Thus, I eliminate any possibility of the contacts bouncing against each other but on the other hand make sure that they will remain in good contact with each other during the further movement of the disc 28 in a clockwise direction.

75 The distance between the flanges 43 is for the

purpose of giving a certain lag in operation (usually about 35 to 50 degrees in stack switch installations). This, of course, is to prevent changing the position of the snap switch unit upon slight changes in temperature as might be caused by increased or decreased draft through the furnace as distinguished from combustion failure or combustion establishment.

The spring arms 36 are initially of the shape shown by dotted lines in Figure 5, so that when 10 the balls 38 are inserted in the seats 37 they will be biased with the desired pressure against the notches 41. The position of the contact 18 is so adjusted that the contacts will remain either open as in Figure 2 or closed as in Figure 3, when 15 once moved to either of such positions.

From the foregoing description of the means for providing a stack switch having the desirable characteristics set forth it is apparent that I have devised a practical and efficient construction. 20 My invention is simple and economical and while the foregoing represents one of the preferred forms of embodiment thereof, I desire to reserve the right to make whatever changes or modifications may fairly fall within the scope of the appended claims.

What I claim as new and desire to secure by Letters Patent of the United States is:

1. In a stack switch, a snap switch unit and temperature responsive mechanism for operating said snap switch unit, said snap switch unit comprising a rectangular frame having an open center, a buckled leaf spring extending between the ends of said frame, a contact carried by said buckled leaf spring, a stationary contact for coaction therewith, a projection from said buckled leaf spring for reversing the curvature thereof to effect opening or closing of said contacts with respect to each other, said temperature responsive mechanism including a rotatable shaft, a temperature responsive element for rotating said shaft, a disc rotatable with said shaft and having a plurality of closely spaced notches in a face thereof, an actuator rotatable relative to said disc and having a plurality of ball elements engaged with said notches to effect rotation of said actuator with said disc as the disc is rotated, said actuator including a leaf spring biasing said ball elements to engage said notches of said disc and a pair of projections beyond the periphery of said disc straddling and thereby operatively coacting with said projection from said buckled leaf spring. 40

2. In a stack switch, a switch unit and temperature responsive mechanism for operating said switch unit, said temperature responsive mechanism including a rotatable shaft, a temperature responsive element for rotating said shaft, a disc rotatable with said shaft and having a plurality of closely spaced notches in a face thereof, an actuator rotatable relative to said disc and having a pair of diametrically opposite ball elements engaged with said notches to effect rotation of said actuator with said disc as the disc is rotated, said actuator including a leaf spring member biasing said ball elements to engage said notches of said disc and means for operatively connecting said leaf spring member with said switch unit. 50

3. In a stack switch, a snap switch unit and temperature responsive mechanism for operating 70 said snap switch unit, said snap switch unit including a buckled leaf spring, a contact carried thereby, a stationary contact for coaction with said first mentioned contact, the curvature of said leaf spring being reversible to effect opening 75

or closing of said contacts with respect to each other, said temperature responsive mechanism including a rotatable disc, a temperature responsive element for rotating said disc, said disc having a plurality of closely spaced notches in a face thereof, an actuator rotatable relative to said disc and having a ball engaged with said notches to effect rotation of said actuator with said disc as the disc is rotated, said actuator being operatively connected with said buckled leaf spring to effect such reversal of curvature thereof.

4. In a stack switch, a switch unit and temperature responsive mechanism for operating said switch unit, said temperature responsive mechanism including a rotatable disc, a temperature responsive element for rotating said disc, said disc having a series of notches therein, an actuator rotatable relative to said disc and having a pair of diametrically oppositely arranged ball elements engaged with said notches to effect rotation of said actuator with said disc as the disc is rotated, said actuator including means biasing said ball element in a direction axially of said disc to engage said notches and means on said 25 actuator operatively coacting with said switch unit to operate it from said actuator.

5. In a stack switch, a snap switch unit and temperature responsive mechanism for operating said snap switch unit, said snap switch unit including a buckled leaf spring, a contact carried by said spring, a stationary contact for engagement therewith, said leaf spring at one curvature closing said contacts and at a different curvature opening them, said temperature responsive mechanism including a rotatable shaft, a temperature responsive element for rotating said shaft, a disc rotatable with said shaft and having a plurality of closely spaced notches in a face thereof, an actuator rotatable relative to said disc having a ball seat, a ball seated therein for contact with the notches of said disc to effect rotation of said actuator with said disc as the disc rotates, means to effect such contact of said ball with said notches, and means of operative coaction between said actuator and said snap switch unit to effect reversal of the curvature of the snap switch by rotation of said actuator from said disc, further rotation of the disc after operation of the snap switch being permitted by the ball and notch connection between said disc and said actuator.

6. In a stack switch, a switch unit and temperature responsive mechanism for operating said switch unit, said temperature responsive mechanism including a rotatable disc, a temperature responsive element for rotating said disc, said disc having a plurality of notches in a face thereof, an actuator rotatable relative to said disc and including a leaf spring member having a ball seat, a ball seated therein for contact under the bias of said leaf spring with the notches of said disc to effect rotation of said actuator with said disc as the disc rotates, said leaf spring having a portion extending beyond said ball seat, curving over the periphery of said disc and terminating on the opposite side thereof, the ter-

minating end serving as a stop portion, and means of coaction between said leaf spring member and said switch unit to effect movement of the switch unit from one position to another by rotation of said actuator from said disc, further rotation of the disc after such movement of the switch unit being permitted by the ball and notch connection between said disc and said actuator. 5

7. In a stack switch, a snap switch unit and temperature responsive mechanism for operating said snap switch unit, said snap switch unit comprising a rectangular frame having an open center, a buckled leaf spring extending from end to end thereof, a contact carried by said spring, a stationary contact for engagement therewith, 15 said leaf spring at one curvature closing said contacts and at a different curvature opening them, said temperature responsive mechanism including a rotatable shaft, a temperature responsive element for rotating said shaft, a disc 20 rotatable with said shaft and having a plurality of notches therein, an actuator rotatable relative to said disc and including a leaf spring member having a plurality of ball seats, balls seated therein for contact under the bias of said leaf 25 spring in a direction normal to the plane of said disc and with said notches to effect rotation of said actuator with said disc as the disc rotates, said leaf spring having portions extending beyond said ball seats and curving over the periphery of said discs and means of coaction between said leaf spring member and the leaf spring of said snap switch to effect reversal of the curvature of the snap switch by rotation of said actuator from said disc, further rotation of 30 the disc after operation of the snap switch being permitted by the ball and notch connection between said disc and said actuator. 35

8. In a stack switch, a snap switch unit and temperature responsive mechanism for operating said snap switch unit, said snap switch unit comprising a rectangular frame having an open center, a buckled leaf spring extending from end to end thereof, a contact carried by said spring, a stationary contact for engagement therewith, said leaf spring at one curvature closing said contacts and at a different curvature opening them, said temperature responsive mechanism including a rotatable disc, a temperature responsive element for rotating said disc, said disc having a plurality of notches in a face thereof, an actuator 40 rotatable relative to said disc and including a leaf spring member having a ball seat, a ball seated therein for contact under the bias of said leaf spring with the notches of said disc to effect rotation of said actuator with said disc as the disc rotates, and means of coaction between said leaf spring member and said switch unit to effect movement of the switch unit from one position to another by rotation of said actuator from said 45 disc, further rotation of the disc after such movement of the switch unit being permitted by the ball and notch connection between said disc and said actuator. 50
